[57] CLAIM

The ornamental design for a doghouse with door flap,
as shown and described.

DESCRIPTION

FIG. 1 is a top, front and right side perspective view of
a doghouse with door flap showing my new design;
FIG. 2 is a front elevational view thereof;
FIG. 3 is a rear elevational view thereof;
FIG. 4 is a top plan view thereof;
FIG. 5 is a right side elevational view thereof, the left
side being a mirror image of the right side shown;
FIG. 6 is a bottom plan view thereof; and,
FIG. 7 is another front elevational view thereof show-
ing the door flap open and behind the holding fingers.
